US0D1102411S

(12) **United States Design Patent** (10) **Patent No.:** **US D1,102,411 S**
(45) **Date of Patent:** **** Nov. 18, 2025**

(54) **WIRELESS REPEATER**

(71) Applicant: **Samsung Electronics Co., Ltd.**,
Suwon-si (KR)

(72) Inventors: **Hyungjun Koo**, Suwon-si (KR); **Jihee Kwak**, Suwon-si (KR)

(73) Assignee: **SAMSUNG ELECTRONICS CO., LTD.**, Suwon-si (KR)

(**) Term: **15 Years**

(21) Appl. No.: **29/931,389**

(22) Filed: **Mar. 6, 2024**

(30) **Foreign Application Priority Data**

Sep. 15, 2023 (KR) 30-2023-0036574

(57) **CLAIM**

The ornamental design for a wireless repeater, as shown and described.

DESCRIPTION

FIG. 1 is a front perspective view of a wireless repeater showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures depict portions of the wireless repeater that form no part of the claimed design.

1 Claim, 8 Drawing Sheets
